UNITED STATES PATENT OFFICE.

WIRT M. REESE AND MARTIN R. ZELL, OF ORRVILLE, OHIO, ASSIGNORS TO
CRYSTAL BURIAL CASE COMPANY, OF SAME PLACE.

BURIAL-CASE.

SPECIFICATION forming part of Letters Patent No. 228,679, dated June 8, 1880.

Application filed March 30, 1880. (Model.)

To all whom it may concern:

Be it known that we, WIRT M. REESE and MARTIN R. ZELL, of Orrville, in the county of Wayne and State of Ohio, have invented a new and valuable Improvement in Burial-Cases; and we do hereby declare that the following is a full, clear, and exact description of the construction and operation of the same, reference being had to the annexed drawings, making a part of this specification, and to the letters and figures of reference marked thereon.

Figure 1 of the drawings is a representation of a side view, partly in section, of my improved burial-case. Fig. 2 is a transverse section thereof, and Figs. 3 and 4 are details.

This invention has relation to improvements in burial caskets, cases, and coffins having a metallic frame and glass, wood, or metal panels.

20 The objects of the invention are, first, to devise easy, simple, and economical means, whereby the panels may be attached to the frame to absolutely prevent leakage through the bottom of the case, casket, or coffin; to provide 25 means for the ready and expeditious attachment of the inside trimming or lining; and, finally, to improve the manufacture of burial-receptacles generally.

The nature of our invention will be clearly 30 understood from the following description, wherein, referring to the drawings, the letter A designates a casket having glass side panels and a similarly-paneled lid.

The bottom B is cast with an erect margin- 35 al flange, a, extending completely around it, and having projecting horizontally from its end portions inward the lugs or eyes b, and similar perforated lugs may be on the side portions of the said flange, if desired. Upon the 40 upper side of the bottom, at proper intervals, are cast the flat screw-seats c, which serve as points of attachment to the right-angular handle-arms c', the said arms passing under the bottom and being secured thereto by screws 45 passing into but not through the seats c aforesaid. With the flange and bottom are cast on the former the vertical ribs d, that serve as guides to the head and foot pieces C C' of the casket, and hold them in place against the cor-

responding portions of the flange a. The parts 50 C C' may be panel-formed, if desired.

The top rim, D, may be cast in one or more pieces, as may be deemed expedient, and is composed of a flat border or rim, d', and a depending flange, d'', the said top frame being 55 T-shaped in cross-section. This rim or frame fits snugly over the end pieces of the casket, and with the parts above enumerated constitutes the frame-work of the body of the coffin, casket, or case. This frame is bound together 60 in rigid form by means of stout metal rods e', passing down through the inner edge of rim d and through the eyes b, that project through slots e in the end and side pieces, C C', and a nut, e'', applied upon the threaded lower ends 65 of said rods below the eyes. By setting up these nuts the end pieces are forcibly clamped by the bottom and top frame and maintained securely in place.

The rim-frame D is cast with edge-recesses 70 i' and wires i, extending across the said recesses, and serving for the attachment of the screen, curtain, or trimming of the interior, the wire being laid in the mold and the rim cast thereon.

75 The panels, which may be of glass, iron, or wood, are arranged to cover from the inside the spaces between the end pieces, the flange a, and the rim-frame D, and are secured to the sides as follows: There are secured to the 80 screw-seats by means of screws s s adjustable slides j, slotted longitudinally for the passage of said screws, and to the inside of the rim-frame similar slides j' by screw-bolts s' s'. The panel being in place, the said slides are pressed 85 up forcibly against it and adjusted by setting up the screws.

As above described, the body of the casket is without holes passing through its bottom, and consequently cannot leak; but if from any 90 cause a hole should have to be made therein, an inverted cup, k, having an edge-flange, l, on its lower edge and filled with cement, is used. The cup is placed over the hole and the screw driven home through it from below.

95 The lid-frame N, which is made in one or more pieces, is also of iron and of panel-frame form, the panel being also of glass, wood, or

iron, and secured in place on the inside by means of slides *o*, of triangular form, and provided with a widened bearing-edge, *p*, and an inclined slot. These slides are secured to a 5 perforated lug on the lid-frame by means of screws passing through the slot of the slides into the said lug; or we may use slides similar to the slides *j* aforementioned.

The object of the slides, independent of their 10 obvious function of holding the panels, is to allow the ready and speedy attachment of glass and other panels to the coffin, even though of varying thickness.

Glass is rarely made of the same thickness 15 exactly, and were the holding devices fixed the panel would scarcely ever fit sufficiently close against the sides of the coffin. By making the slides adjustable this defect is readily overcome.

20 We are aware that side moldings of a burial-case having bent strips or hooks cast therein to retain the cloth lining is not new; and we do not claim a coffin having shoulders between its bottom and sides and handles secured 25 thereto.

What we claim as new, and desire to secure by Letters Patent, is—

1. In a burial case, casket, or coffin, the combination, with the one-piece bottom *B*, having 30 the erect marginal flange *a* and the horizontal

eyes projecting therefrom, the end pieces, *C C'*, and the rim-frame *D*, of the headed bolts *e'*, extending downward through said rim and eyes, and the nuts *e''* upon the lower ends of said bolts below the eyes, substantially as 35 specified.

2. The combination, with the casket, having open sides and detached panels closing said openings, of the slotted adjustable slides *j j'* and set-screws *s*, substantially as specified. 40

3. The top rim, *D*, cast with recesses *i* in its inner edge, and wires *i'*, extending across said recesses, for the attachment of the inside trimmings, the wire being laid in the mold and the rim cast thereon, substantially as specified. 45

4. The one-piece cast coffin or casket bottom *B*, having the raised screw-seats *c*, the erect edge-flange *a*, and the perforated lugs *b*, for assembling the parts of the receptacle and avoiding perforations in the bottom, substantially as specified. 50

In testimony that we claim the above we have hereunto subscribed our names in the presence of two witnesses.

WIRT M. REESE.
MARTIN R. ZELL.
